REFRIGERATION APPARATUS

Carl Sundbach, East Weymouth, Mass.

Application September 7, 1938, Serial No. 228,859

4 Claims. (CL. 62—126)

This invention relates to refrigeration apparatus, and has special reference to the construction and arrangement of the plates of a so-called "plate freezer" adapted primarily for use with a refrigerant capable of producing cold upon the direct expansion principle, and the freezer plates being included in what is known as a flooded system, under float-valve control.

In the use of refrigerants operating upon this principle, low pressures or partial vacuum will be established when the refrigerant, in the process of producing cold, changes from a liquid to a gaseous phase, and high pressures will result when a rise in temperature takes place during a shut-down of the apparatus. In view of these conditions, those plate freezers with which I am familiar employ means other than the structure of the plates themselves for confining the refrigerant and preventing fracture of the plates and escape of the refrigerant to the atmosphere.

Inasmuch as the refrigerant most commonly employed in apparatus operating upon this principle is ammonia, which is noxious and toxic, it is important that it be safely confined. There are, of course, other refrigerants suitable for direct expansion, such as dichlorodifluoromethane and methylene chloride, which, although not noxious or toxic, must be safely confined.

The object of the invention is to provide a plate freezer, the plates of which are of relatively thin-walled construction for purposes of efficiency in reducing loss of effect of the refrigerant, and in so connecting these walls as to provide a strong and rigid construction which will not fail in the presence of the high pressures prevailing. Furthermore, by constructing the plates in the manner hereinafter specifically set forth, I am enabled to provide for thorough and ready circulation of the refrigerant throughout the interior of the plates.

The plates may, as will hereinafter appear, be mounted in tiers of as many units as may be desired, and may accommodate between them the materials or articles to be frozen, and means for mechanically applying pressure to the tier of plates is provided as is customary.

In the accompanying drawing illustrating the invention, in the several figures of which like parts are similarly designated,

Figure 1 is a front view of a plate freezer embodying the invention.

Fig. 2 is a side view thereof.

Fig. 3 is an enlarged sectional elevation of one of the plates.

Fig. 4 is an enlarged sectional elevation, the

section of which is taken at right angles to that of Fig. 3, and

Fig. 5 is a fragmentary plan view showing a modification.

Referring particularly to Figs. 1 and 2, it will be seen that the plate freezer of the invention may comprise a base 1, above which is arranged the series or tier of freezer plates 2 guided upon columns 3 and normally spaced apart by springs 4. The columns are fastened to the base 1 in suitable supports 5 and their upper ends are connected with a plate 6 by which they are held in rigid spaced relation.

The plate 6 carries a strengthening rib 7, or is otherwise provided with a suitable bearing member 8 which carries a pressure-applying screw 9 the lower end of which bears against the uppermost plate 2 of the tier, as indicated at 10, and the upper end of which may be provided with a hand wheel 11, or other suitable means whereby the screw 9 may be either manually or mechanically rotated, as is usual, to apply pressure to the tier of plates and the articles A to be frozen positioned between them, and to release such pressure.

An inlet manifold 12 is arranged at one side of the freezer and has flexible tubular members or pipes 13 connecting it with the several plates 2. At the opposite side of the freezer there is an outlet manifold 14 having similar flexible connections 15 with the several plates.

It will be noted that the lowermost plate 2 of the series is preferably rigidly supported upon the members 5, but that the plates arranged above it (and they may be of any desired number, as hereinbefore mentioned) are vertically movable upon the columns 3. Thus, when pressure of the screw 9 is released the plates will automatically separate under the influence of the springs 4 so that the articles A, such as packages of food products or other commodities, may be positioned between them or may be removed after freezing.

Each of the plates, as illustrated particularly in Figs. 3 and 4, comprises an upper wall member 16 and a similar lower wall member 17 of metal of appropriate thickness and physical characteristics, the transverse edges of which abut against and are preferably welded, as indicated at 18, to end members 19 which may be rabbeted, as shown, to receive them, and which form the end edges of the plates. The longitudinal edges of the wall members 16 and 17 pass within tubular closure members 20 and 21, which serve as inlet and outlet means, respectively, and are

preferably welded thereto as indicated at 22. At appropriate intervals within the freezer plates, spacer members 23 are arranged between the wall members 16 and 17 and stay-bolted thereto, as indicated at 24, thus preventing the freezer plates from collapsing upon the application of pressure thereto under the influence of screw 9, and from bulging under the influence of the confined expanding refrigerant.

Suitably welded spacing and guide sleeves 25 may be provided (Fig. 3) adjacent to the corners of the freezer plates to receive the columns 3 and guide the plates upon these columns in appropriate vertical alignment, or, as shown in Fig. 5, the guide means 25' may be arranged exteriorly of the plates at their corners.

The ends of the closure members 20 and 21, where they embrace the abutting ends of the end members 19 may be filled in and thus closed, fluid tight, in any appropriate manner as by suitable filler blocks or by the welding metal indicated at 26.

Obviously, the thickness of the wall members 16 and 17 of the freezer plates, and the strength of the stay bolt connections 23, 24 will depend upon the pressure normally to be confined.

It will be apparent that by employing freezer plates of the type of construction contemplated by my invention, the refrigerant upon entering the inlet closure member 20 will have an opportunity to reach every part of the interior of the plates rapidly and effectively and without encountering any tortuous passages or any means tending to block its ready circulation. As the refrigerant, for example ammonia, changes from its liquid to its gaseous phase it may readily escape from the plate through the closure member 21. The inlet and outlet closure members 20 and 21 being of relatively large size, and extending in an unobstructed arrangement longitudinally of the edges of the plate, make possible rapid and effective distribution and collection, respectively, of the refrigerant in its two phases as it enters and leaves the plate.

Although the plates of the invention have been described as particularly adapted for use in plate freezers employing a refrigerant operating upon the direct expansion principle, it will be apparent that they may be employed to advantage in refrigerators or plate freezers employing brine or other secondary refrigerants. When so used their efficiency will be enhanced by the presence of the closure members 20 and 21 and by the fact that, as in their use with refrigerants operating upon the direct expansion principle, there are no baffles or other members tending to obstruct free flow of the refrigerant throughout the plate interior.

Various changes and modifications are con-

sidered to be within the spirit of the invention and the scope of the following claims.

What I claim is:

1. In a plate freezer, a freezer plate of relatively flat hollow form, including an upper wall member and a lower wall member, end members provided with rabbets arranged in edge-abutting relation with and at opposite ends of said wall members and to which the wall members are connected in fluid tight manner, closure members connected fluid tight to opposite sides of said wall members and embracing the ends of said end members, and means disposed between said wall members at predetermined points throughout their area for maintaining the wall members in predetermined spaced relation.
2. In a plate freezer, a freezer plate of relatively flat hollow form, including an upper wall member and a lower wall member, end members arranged in edge-abutting relation with and at opposite ends of said wall members and to which the wall members are connected in fluid tight manner, closure members embracing the side edges of said wall members and the ends of said end members and connected fluid tight thereto, and means disposed between said wall members at predetermined points throughout their area for maintaining the wall members in predetermined spaced relation.
3. In a plate freezer, a freezer plate of relatively flat hollow form, including an upper wall member and a lower wall member, end members provided with rabbets arranged in edge-abutting relation with and at opposite ends of said wall members and to which the wall members are connected in fluid tight manner, closure members embracing the side edges of said wall members and the ends of said end members and connected fluid tight thereto, and means disposed between said wall members at predetermined points throughout their area for maintaining the wall members in predetermined spaced relation, said closure members provided with means for connecting the plate with refrigerant introduction and emission means.
4. In a freezer plate of relatively flat hollow form an upper wall member and a lower wall member supported and connected fluid tight at their edges, spaced members disposed between said wall members at predetermined points throughout their area and serving to maintain said wall members in predetermined spaced relation, certain of the spacer members of said plates being provided with bores through which aligning and guiding columns pass to provide for arrangement of a plurality of the plates in an operative tier.

CARL SUNDBACH.
